FLOWER STAND

Filed Oct. 6, 1928

By
Watson E. Colemant

UNITED STATES PATENT OFFICE

JOHN F. RUSH, OF INDIANAPOLIS, INDIANA

FLOWER STAND

Application filed October 6, 1928. Serial No. 310,817.

This invention relates to flower stands and it is an object of the invention to provide a device of this kind which is particularly adapted for use in connection with floral pieces.

It is also an object of the invention to provide a device of this kind which, when not in use, may be readily collapsed and which also may be employed with especial advantage with the carrying of the flowers as from the home or church to the flower vehicle or from the vehicle within the church.

An additional object of the invention is to provide a device of this kind which, when in use, is adapted to be placed adjacent to the casket either within the home or church in order to provide an effective display of the floral pieces.

The invention consists in the details of construction and in the combination and arrangement of the several parts of my improved flower stand whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view in perspective of a flower stand constructed in accordance with an embodiment of my invention;

Figure 2 is a fragmentary vertical sectional view taken through a side marginal portion of the stand as herein employed;

Figure 3 is a fragmentary view in top plan of a corner portion of the stand as herein disclosed.

My improved stand, as herein disclosed, comprises a table section T consisting of a frame 1 of desired configuration and dimensions and which supports a grid-like structure 2, the cross members of which being engaged from above with the frame 1 and

soldered or otherwise fixedly secured thereto.

Each end member 3 of the table T has disposed therealong from above and soldered or otherwise fixedly secured thereto a bar 55 or rod 4, said rod extending a desired distance beyond each side of the frame 1 and continued by the inwardly disposed arms 5. These arms 5 provide handles whereby the table may be readily transported and particularly when it is desired to convey the floral pieces thereon from one location to another.

In the present embodiment of my invention, each of the end members 3 has pivotally engaged therewith the supporting legs 6 of desired length, the pair of legs 6 at each end of the table being tied or connected for unitary swinging movement by a cross member 7.

The outward swinging movement of each pair of legs 6 is limited by a chain 8 or kindred flexible member having one end portion anchored, as at 9, to the central part 75 of the cross member 7 and its opposite end portion connected, as at 10, to one of the longitudinal members 11 comprised in the grid structure and more particularly the central member 11.

When not in use the legs 6 may be readily 80 swung up in close proximity to the table T and are also adjusted into such position when it is desired to carry the table with its load from one location to another.

Each side member of the frame 1 also has operatively engaged therewith a plate 12 upon which may be suitably produced the name of the undertaker or other notice desired.

Each of the side members of the frame also has hingedly connected thereto a side member 14 which, when in its lifted or raised position, provides means against which baskets of flowers or certain types of 95 set pieces may be readily positioned, and the upward swinging movement of this side member 14, as herein disclosed, is limited by a chain or kindred flexible member 15 co-acting with each side member 14' and herein 100

disclosed as suitably anchored to a cross member 2.

From the foregoing description it is thought to be obvious that a flower stand constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:-

1. A flower stand comprising, in combination, a wire table structure, foldable leg members carried by said table, guard members swingingly carried by said table, and handle members mounted on the opposite ends of said table.

2. A flower stand comprising, in combination, a wire table structure, leg members carried by said table, said leg members being adapted to swing inwardly whereby to provide a compact folded structure, stop means adapted to hold the legs in upstanding position, guard members swingingly mounted in the side portions of said table, and handles mounted on the opposite end portions of the table.

In testimony whereof I hereunto affix my signature.

JOHN F. RUSH.
